Primary Examiner — Sandra Snapp(74) *Attorney, Agent, or Firm* — Quarles & Brady LLP(57) **CLAIM**

The ornamental design for a dispenser device, as shown and described.

DESCRIPTION

FIG. 1 is an isometric view of a rear, top, and left side of an ornamental design for a dispenser device;

FIG. 2 is a rear elevational view of the dispenser device of FIG. 1;

FIG. 3 is a front elevational view of the dispenser device of FIG. 1;

FIG. 4 is a right side elevational view of the dispenser device of FIG. 1, wherein the left side elevational view is a mirror image of the right side elevational view;

FIG. 5 is a top plan view of the dispenser device of FIG. 1; and,

FIG. 6 is a bottom plan view of the dispenser of FIG. 1. The broken lines are for the purpose of illustrating environmental structure and form no part of the claimed design.
